Primary Examiner — David Muller*Assistant Examiner* — Nathan Johnston(74) *Attorney, Agent, or Firm* — Yokoi & Co., U.S.A.;
Toshiyuki Yokoi(57) **CLAIM**

The ornamental design for an exhaust cleaner for fluid pressure device, as shown and described.

DESCRIPTION

FIG. 1 shows a front view of an exhaust cleaner for fluid pressure device showing my new design;

FIG. 2 shows a rear view thereof;

FIG. 3 shows a right side view thereof;

FIG. 4 shows a left side view thereof;

FIG. 5 shows a top view thereof;

FIG. 6 shows a bottom view thereof;

FIG. 7 shows a bottom, front and left side perspective view thereof;

FIG. 8 shows a top, front and right side perspective view thereof; and,

FIG. 9 shows an enlarged cross-sectional view thereof, taken along line 9-9 in FIG. 1.

The portions of the design shown in broken lines in FIGS. 1-9 are for the purpose of illustrating the environment only and form no part of the claimed design.

The present article is an exhaust cleaner used for cleaning exhaust air of a fluid pressure device. The exhaust cleaner includes hollow fiber membranes. A joint located on the right side end in the cross-sectional drawing is connected to an exhaust port of the fluid pressure device so as to clean the exhaust air fed to the exhaust cleaner by the hollow fiber membranes and to discharge the exhaust air from an opening of the hollow fiber membranes located on the left side end.
